UNITED STATES PATENT OFFICE.

CHARLES J. SHIRREFF, OF BROCKVILLE, ONTARIO, CANADA, ASSIGNOR OF ONE-HALF TO RICHARD THOMAS STEELE, OF SAME PLACE.

CLOTHES-WRINGER.

SPECIFICATION forming part of Letters Patent No. 244,325, dated July 12, 1881.

Application filed March 28, 1881. (No model.) Patented in Canada January 17, 1881.

To all whom it may concern:

Be it known that I, CHARLES JAMES SHIRREFF, of Brockville, in the county of Leeds, in the Province of Ontario, Canada, have invented 5 certain new and useful Improvements in Clothes-Wringers; and I do hereby declare that the following is a full, clear, and exact description of the same.

This invention relates to the combination, 10 with a clothes-wringer, of a frame by which the wringer is attached to a tub, and an apron-frame carried by the same, having arms pivoted eccentrically to the frame, so that by the adjustment of the apron from a vertical to a 15 horizontal position the frame clamps the wringer to the edge of the tub and supplies a means for conveying the clothes to or from the rollers into the tub.

Figure 1 is a side elevation of a clothes- 20 wringer having my combined clamp and apron device. Fig. 2 is an end elevation of the same.

A A are the standards of an ordinary wooden-frame wringer, in which are journaled the rollers B B, geared together, and compressed 25 by bar C, spring D, and set-screw E, in the usual way.

F are the legs of the clamp-frame, held to the standards A, which are notched to some- 30 what less than the thickness of an ordinary tub-stave, by a bolt, G, passing through an elongated hole in the legs F, whereby an adjusting motion is allowed thereto to bind against the side of the tub when the clamping-power is applied, as hereinafter described.

The bolts G pass through a yielding cushion, H, or a suitable spring intervening between the leg and standard and through the standard, the ends provided with a thumb-screw, I, to contract or expand the spring or cushion to 35 suit the space J to the thickness of the stave of the tub.

From the top downward to a suitable extent the legs F are slotted, as shown at K, to receive cam-brackets L, which are provided with 40 a downward prolongation, a, to bear against the standards A or a fixed block, b, thereon, to support the brackets horizontally, which are pivoted eccentrically in the slot K, so that

the end of the brackets, by cam movement, will force out the upper end of the legs, and 50 by pivotal movement on the bolt G cause the lower ends to bind against the side of the tub and compress it against the standards A for fixing the wringer to the edge of the tub.

The brackets L at their outer ends are pro- 55 vided with side sockets, N, into which fit the ends of a hand-bar or roller, O, and said brackets support rollers P, journaled thereto inter- medately on screws Q, to form an apron-frame, on which the clothes are carried from or to the 60 wringer-rollers, according to which side of the wringer the frame is placed.

For stability the legs F are connected by a bar, R.

When the apron-frame is placed on the out- 65 side of the wringer, the clothes, after pass- ing from the washing-tub, are passed through the rollers and carried therefrom upon the apron-frame, so as to be deposited in an ad- joiningly-placed tub without distributing the 70 clothes therein by hand. When the apron- frame, consisting of the brackets L and rollers O P, is raised from a horizontal to a vertical position, as shown in dotted lines in Fig. 2, the legs F will be released from the tub for the 75 removal of the wringer. When the apron-frame is attached to that side of the wringer outside the washing-tub, the clothes are conveyed to fall into the adjoining receiving-tub, so that the tub will be filled without distributing the 80 clothes therein by hand.

I claim as my invention—

1. The combination, with the wringer-frame A, of the legs F, bolts G, and cam-brackets L, having downward prolongation a, and car- 85 rying rollers O P, as and for the purpose set forth.

2. An apron-frame consisting of cam-brack- 90 etts L and rollers O P, said cam-brackets being eccentrically pivoted within slot K to legs F, attached to standard A, as and for the purpose set forth.

C. J. SHIRREFF.
